UNITED STATES PATENT OFFICE

2,370,475

METHOD AND APPARATUS FOR TESTING
SEALED ENVELOPES

Eugene Lemmers, Cleveland Heights, Ohio, assignor to General Electric Company, a corporation of New York

Application January 21, 1942, Serial No. 427,597

8 Claims. (Cl. 315—246)

My invention relates to method and apparatus for the production of a high frequency glow discharge within a sealed container. More particularly, my invention relates to method and apparatus for testing photoflash lamps of the well-known type used for photographic purposes for the presence of air within the sealed bulb thereof by the production of a high frequency glow discharge therein.

As a safeguard against explosion of the glass bulb when flash lamps of the above type are flashed, it is common practice, in the manufacture of such flash lamps, to test the completed lamp for the presence of air. One well-known method of conducting such a test, known as a coil or glow test, consists in the use of high frequency equipment for the production of a high frequency glow discharge within the sealed lamp bulb. By observing the color of the glow discharge produced in the lamp bulb, the presence or absence of air therein can then be readily determined, a pale bluish-green glow discharge denoting a good lamp containing the normal oxygen gas filling with no air present and a purplish or pink-colored discharge indicating a lamp into which air has leaked.

Heretofore, in such high frequency glow testing of flash lamps, it has been customary to connect one side of the high frequency circuit to the lamp leading-in wires through the lamp base, and the other side to an external electrode placed closely adjacent the top of the lamp bulb. However, such an arrangement is apt to produce a spark or discharge within the lamp bulb at the primer bead or fulminating substance therein, or at a point closely adjacent thereto, which will result in the ignition of the primer bead or fulminating material with consequent flashing of the lamp. This is particularly true in the case of flash lamps of the fulminating bead type disclosed and claimed in copending application Serial No. 328,399, Marvin Pipkin, filed April 8, 1940, now Patent 2,291,983, issued August 4, 1942, in which the light-producing material consists solely of one or more beads or coatings of a readily ignitable fulminating material disposed on the tips of the inner lamp leads. To overcome this defect, therefore, it has been found necessary to provide suitable means, preferably in the form of an electrical conductor or antenna connected to one of the inner lamp leads and extending to a point within the bulb considerably removed from the fulminating material, for confining the glow discharge to an area within the bulb considerably removed from the fulminating material so as to prevent the discharge from striking the fulminating material and accidentally igniting the same with resultant premature flashing of the lamp. Such a flash lamp construction is shown and claimed in the copending

applications of D. E. Elmendorf, Serial Nos. 371,318 and 384,622, filed December 23, 1940, and March 22, 1941, respectively, the latter of which is now Patent 2,342,575, issued February 22, 1944.

5 While such a flash lamp construction is entirely satisfactory insofar as the prevention of flash-outs during the high frequency testing of the lamp is concerned, nevertheless the use of the conductor or antenna member complicates the manufacture of the flash lamp and increases its cost somewhat.

One object of my invention is to provide a method and apparatus for producing a high frequency discharge in a given portion of the space

15 within a sealed envelope. Another object of my invention is to provide a method and apparatus for producing, in a sealed envelope, a high frequency discharge between two relatively closely spaced points on the wall of the envelope by the application of the high frequency electrodes to the external surface of the envelope wall.

20 Still another object of my invention is to provide a method and apparatus for testing flash lamps for the presence of air therein by the production of a high frequency discharge in the sealed lamp bulb which will not set off and prematurely flash the lamp.

25 A further object of my invention is to provide a method and apparatus for producing a high frequency discharge within the sealed bulb of a flash lamp between two spaced points on the bulb surface such that the discharge path within the bulb is remote from the fulminating material disposed therein.

30 An important feature of the invention is the provision of two spaced electrodes which are connected to the opposite terminals of a source of high frequency current and which are adapted to be placed in contact with or closely adjacent the sealed flash lamp bulb at two spaced points on the curved surface thereof so that the discharge gap therebetween is remote from the fulminating material in the lamp bulb, together with 35 a liquid insulating medium disposed between the said electrodes and contacting that portion of the bulb wall between the said spaced points thereon engaged by the electrodes so as to compel the high frequency discharge between the electrodes to pass through the interior of the lamp bulb rather than along the exterior surface thereof.

40 Further objects and advantages of my invention will appear from the following description of 45 a species thereof and from the accompanying drawing which is a diagrammatic illustration of an arrangement according to the invention for testing flash lamps for the presence of air therein.

50 Referring to the drawing, the apparatus, ac-

cording to the invention, comprises an upright cup-shaped receptacle or container 10 of suitable insulating material such as a heat-resistant glass, preferably "Pyrex," having a seat 11 in its bottom wall against which the curved surface of the lamp bulb to be tested is adapted to rest. The seat 11 is provided with a centrally located recess 12 which is filled with a very heavy electrically conductive liquid 13 of high density, such as mercury. The mercury filling 13 forms one of the high frequency discharge electrodes of the device. For making electrical connection from the exterior of the cup 10 to the mercury filling 13 therein, a leading-in wire 14 is sealed through the bottom wall of the glass cup 10 so as to extend into and terminate within the mercury filling.

Filling the receptacle 10 up to a level high enough to just cover the mercury 13, for instance, about $\frac{1}{8}$ " to $\frac{1}{4}$ " or so, is a suitable liquid insulating medium 15. A supernatant 16, in the form of a suitably electrically conductive liquid, covers the liquid insulating medium 15 to a depth of about $\frac{1}{2}$ " or so. The supernatant electrically conductive liquid 16 serves as the other high-frequency discharge electrode of the device. The two liquids 15 and 16 should be immiscible in one another and, in addition, the electrically conductive supernatant 16 should be of appreciably lower specific gravity than that of the liquid insulating medium 15, so that the two liquids 15, 16 will maintain their separate state at all times with the liquid insulating medium 15 always at the bottom of the receptacle 10. The electrically conductive supernatant 16 may conveniently consist of water. In such case, the liquid insulating medium 15 preferably consists of either trichloroethylene or carbon tetrachloride. However, any other suitable liquid mediums possessing the requirements mentioned above may be employed.

Disposed concentrically within the receptacle 10 and resting against the bottom wall thereof is an inverted dish-shaped support member 17 of insulating material, such as glass, having a centrally located opening 18 therein through which projects the bulb 19 of the flash lamp 20 to be tested. The said opening 18 is located below the point of maximum diameter of the lamp bulb 19 and is of such a diameter that the periphery thereof just engages the wall of the bulb when the tip portion 21 of the latter is seated in proper position in the seat 11 at the bottom of the receptacle 10. The peripheral wall of the opening 18 thus serves to support the bulb 19 in an upright position within the receptacle 10.

When the lamp is in proper testing position within the receptacle so that the tip portion 21 of the bulb 19 contacts the mercury 13 in the seat 11, the liquid insulating medium 15 and the supernatant liquid electrode 16 will also contact the surface of the bulb at different points thereof. The insulating medium 15, however, because of its greater specific gravity than that of the supernatant liquid 16, will always separate the supernatant liquid 16 from the mercury 13 and will always contact a definite length or portion 22 of the bulb surface between the portion 21 in contact with the mercury 13 and the portion 23 in contact with the supernatant liquid 16.

To produce the high frequency discharge within the lamp bulb, the mercury electrode 13 and the supernatant electrode 16 are connected to a suitable source of high frequency current of high potential. Thus, the supernatant 16 may be grounded, as shown, and the mercury 13 con-

nected, by leading-in wire 14, to one end of the secondary 25 of a Tesla coil 24, the other end of which is grounded. The primary 26 of the Tesla coil is then connected to a suitable source 27 of high frequency current, as shown.

When the high frequency source 27 is energized, and the lamp 20 is inserted in proper testing position within the receptacle 10, a high frequency glow discharge is formed within the lamp bulb 19 between the two electrodes 13 and 16; and because of the application of the high frequency to portions 21, 23 of the bulb remote from the fulminating material 28 of the flash lamp, the glow discharge is formed at a point within the bulb likewise remote from the fulminating material 28. Consequently, there is no possibility of the glow discharge accidentally igniting the fulminating material 28 and so prematurely flashing the lamp. By visually observing the color of the high frequency glow discharge produced within the lamp bulb, the presence or absence of air therein can then be readily determined.

The use of an insulator 15 of liquid form, which 25 intimately contacts the outer surface of the bulb wall, enables the formation within the bulb of a glow discharge of relatively small size between two relatively closely spaced points on the bulb wall. Without such a liquid insulator 15, the 30 discharge would form exteriorly of the bulb, since the breakdown potential of the air gap between the relatively closely spaced external electrodes would be less than the breakdown potential of the space within the bulb which is adjacent to 35 such electrodes. The above indicated possibility of forming a very small discharge between two relatively closely spaced points on the bulb wall is of particular utility in the case of flash lamps of the above mentioned fulminating bead type 40 employing a bulb of relatively small size, since with such small sized flash lamps the glow discharge within the bulb must be confined to a relatively small area therein remote from the fulminating material in the bulb if ignition of such fulminating material by the glow discharge, and therefore premature flashing of the lamp, is to be avoided.

The presence of the liquid insulating medium 15 between the supernatant liquid electrode 16 and the mercury 13 in an amount sufficient to 50 prevent a breakdown thereof, and the intimate contact of the liquid insulating medium 15 with the intervening surface 22 of the bulb wall, prevents the passage of the high frequency discharge between the electrodes 13 and 16 along the outside surface of the bulb wall. In this manner, the formation of the high frequency discharge within the lamp bulb, rather than exteriorly thereof, is positively assured.

In place of determining the presence or absence 60 of air within the lamp bulb by visual examination of the color of the high frequency glow discharge produced therein, such determination can be made instead by means of a reading on a suitable form of meter. Thus, one or more photoelectric cells 29 having a substantial sensitivity to the so-called near ultraviolet radiations, i. e., radiations having a wave length of from about 3400 to 3600 Angstrom units, may be disposed 65 within the receptacle 10 so as to be directed or pointed at that portion of the flash lamp bulb 19 within which the high frequency glow discharge is formed during the testing of the lamp. In addition, a suitable cover or shield 30 is arranged 70 to cover the receptacle 10, when the lamp 20 is 75

in proper test position therein, to act as a light trap serving to prevent any light exteriorly of the receptacle from entering the latter and exciting the photoelectric cells 29 therein. Preferably, the cover or shield 30 is in the form of two metal plates having recesses 31 therein for the accommodation of the base 32 of the lamp to be tested, the plates being pivotally mounted to rotate about a vertical axis so as to permit insertion of the lamp in, and removal from the receptacle 10.

By connecting the photoelectric cells to a suitable galvanometer or other current measuring device (not shown), the readings recorded by such meter will then readily and accurately indicate the absence or the presence of air within the lamp bulb. Thus, a good flash lamp having no air present in the bulb but only the normal oxygen gas filling therein, will yield substantially no reading on the galvanometer since a discharge in oxygen gives substantially no radiations in the ultraviolet region, to which radiation the photoelectric cells 29 are predominantly sensitive. On the other hand, any lamp having air (and therefore nitrogen) present in the bulb, will give at least an easily readable deflection of the galvanometer needle since a mere trace of nitrogen in the bulb will cause the glow discharge to emit a substantial amount of radiations in the 3400 to 3600 Angstrom unit band to which radiation the photoelectric cells 29 are particularly sensitive.

Where the flash lamp to be tested is of the fulminating bead type shown in the drawing, and described and claimed in the above mentioned Pipkin Patent 2,291,983, then the lamp is preferably provided with a small internal electrode or conductive member disposed within the top portion of the bulb on the inner surface of the bulb or extending alongside thereof, as disclosed and claimed in my copending application Serial No. 427,598 filed of even date herewith, now Patent 2,316,344, issued April 13, 1943. Such an internal electrode or conductor member serves to shorten the discharge gap through the space within the lamp bulb between the external mercury electrode 13 and the external liquid electrode 16, and therefore facilitates the starting of the glow discharge within the lamp bulb.

What I claim as new and desire to secure by Letters Patent of the United States is:

1. Apparatus for producing a high frequency discharge in a sealed envelope of insulating material comprising a receptacle having a quantity of mercury disposed therein at the bottom thereof, a liquid insulating medium in said receptacle covering the said mercury, a supernatant on said liquid insulating medium consisting of an electrically conductive liquid immiscible with and of lower specific gravity than said liquid insulating medium, and a source of high frequency current connected to the said mercury and the said electrically conductive supernatant.

2. Apparatus for producing a high frequency discharge in a sealed envelope of insulating material comprising a receptacle having a quantity of mercury disposed therein at the bottom thereof, a liquid insulating medium in said receptacle covering the said mercury therein, said liquid insulating medium being immiscible with and of higher specific gravity than water, a supernatant on said liquid insulating material consisting of water, and a source of high frequency current connected to the said mercury and the said water supernatant.

3. Apparatus for determining the presence of air in a sealed envelope, said apparatus compris-

ing a substantially light-tight container in which the sealed envelope to be tested is positioned, means for producing a high frequency glow discharge within said envelope, a photoelectric cell arranged to be exposed to the radiation of the said glow discharge in said envelope, said photoelectric cell having a substantial sensitivity to radiations in the near ultraviolet region which are produced when atmospheric nitrogen is present in the envelope, and indicating means for indicating the degree of excitation of said photoelectric cell.

4. The method of producing a high frequency discharge in a sealed envelope of insulating material which comprises immersing a portion of the envelope in a liquid medium comprising two separate and distinct electrically conductive liquids, separating said liquids by a relatively thin layer of a liquid insulating medium so that the outer surface of the said portion of the envelope is in contact with both of said electrically conductive liquids and connecting said electrically conductive liquids to a source of high frequency current to thereby produce a high frequency glow discharge within the said portion of the envelope.

5. Apparatus for testing the atmosphere in sealed bulbs of insulating material by a high frequency discharge comprising a pair of electrodes adapted to engage and terminate at the exterior bulb surface at spaced points thereon, a source of high frequency current connected to said electrodes, and an insulating medium so disposed in the space between said electrodes as to intimately contact the exterior surface of the bulb and inhibit passage of the discharge through any path outside the bulb.

6. Apparatus for testing the atmosphere in sealed bulbs of insulating material by a high frequency discharge comprising a receptacle containing a pair of spaced electrodes separated by a liquid insulating medium, one of said electrodes being below the surface of said insulating medium, the said electrodes being so spaced and arranged that upon insertion of a portion of a bulb therebetween they engage the exterior surface of the bulb at spaced points thereon and the liquid insulating medium contacts the exterior bulb surface between the electrodes to inhibit passage of the discharge through any path outside the bulb, and a source of high frequency current connected to said electrodes.

7. Apparatus for testing the atmosphere in sealed bulbs of insulating material by a high frequency discharge comprising a receptacle having an electrode at the bottom thereof, a liquid insulating medium in said receptacle covering the said electrode, a supernatant on said liquid insulating medium consisting of an electrically conductive liquid immiscible with and of lower specific gravity than said liquid insulating medium, and a source of high frequency current connected to the said electrode and the said supernatant.

8. The method of producing a localized high frequency discharge in a sealed glass envelope which comprises connecting a source of high frequency to a pair of electrodes, placing said pair of electrodes against closely spaced points on the external surface of said envelope and inhibiting passage of the discharge through any path outside the envelope by maintaining an insulating medium in intimate contact with the portion of the envelope between said electrodes.
